TIRE

Aristides Makris, New Canaan, Conn., assignor to The
B. F. Goodrich Company, New York, N.Y., a corpora-
tion of New York

Filed Apr. 24, 1968, Ser. No. 11,608

Term of patent 14 years

(Cl. D90--20)

The figure is a perspective view of a tire showing the new design, it being understood that the opposite side of the tire is substantially like the side shown.

The dominant features of the design reside in the portions shown in full lines.

I claim:

The ornamental design for a tire, substantially as shown and described.
